(57) CLAIM

The ornamental design for a housing for a wireless adapter, as shown and described.

DESCRIPTION

FIG. 1 is a perspective view of a housing for a wireless adapter showing my new design;

FIG. 2 is a left side view thereof;

FIG. 3 is a right side view thereof;

FIG. 4 is a top view thereof; and,

FIG. 5 is a front view thereof.

The broken line showing of various features is for illustrative purposes only and forms no part of the claimed design. The unshown bottom and rear surfaces of the housing form no part of the claimed design.
